UNITED STATES PATENT OFFICE.

GEORGE W. HENRY, SR., OF MCLEAN COUNTY, ILLINOIS.

NUT-HOLDER AND JOINT-SUPPORTER FOR RAILROAD-RAILS.

943,543.

Specification of Letters Patent. Patented Dec. 14, 1908.

Application filed November 26, 1907. Serial No. 433,984.

To all whom it may concern:

Be it known that I, GEORGE W. HENRY, Sr., a citizen of the United States, residing in McLean county, and State of Illinois, 5 have invented a new and useful Device in Nut-Holders and Joint-Supporters for Railroad-Rails, of which the following is a specification.

My invention relates to improvements in 10 nut holders and joint supporters for railroad rails; and the objects of my improvement are, first, to provide a lock or holder to prevent the turning of the nuts used for fastening railroad rails; and second, to provide an additional support for the joints of 15 railroad rails. I attain these objects by the device illustrated in the accompanying drawings, in which,—

Figure 1 is a side view of the outside 20 holder in place; Fig. 2 is a vertical view of the inside holder detached; Fig. 3 is a vertical view of the outside holder detached with an alternative method of flange making; and Fig. 4 is a cross section through 25 one of the bolts of the railroad rail.

Similar letters refer to similar parts throughout the several views.

The device consists of two angularly shaped bars of any suitable metal, preferably malleable iron, of length equal to that of the ordinary fish or angle bars used on railroad rails, 30 and of a thickness equal to that of the nuts used on said rails, or of a thickness less than this if desired, and adjusted to fit on each 35 side of every joint in the rail.

The upper part, or edge, M, of each bar as shown in Figs. 1 and 2, is made to fit squarely under the nuts, A—A, fitted to the bolts, I, which pass through the railroad rail, D, and 40 the fish bars, C—C, of ordinary railroad rail, thus completely locking them and preventing their turning; the same result is obtained if half the bolts of railroad use are turned inward at each joint and half outward, for as 45 there are two bars the inner, Fig. 2, and the outer, Fig. 3, the upper edge of each fits immediately under the bolt-heads H, and the nuts, A—A.

In Fig. 3 an alternative form is shown in 50 which the upper edge of one bar is cut providing a series of projections adapted to ex-

tend between the nuts A—A, which are by this means locked on three sides and rendered immovable.

At the base of the upright portion of each 55 bar an angular turn is made to adapt the bars for fitting over the edges of the rail, D, and at the outer edge of each side of the base of the railroad rail another angular turn is made to permit the bases or sides of each 60 bar, F, in Fig. 2, and G in Fig. 3 to pass entirely under the rail; in the case of the inner bar, the base or shoe, F, passes clear across to the opposite edge of the base of the railroad rail, if so desired, the outer base or 65 shoe, G, passes clear across the base of the railroad rail and beyond as shown in Fig. 4. These bars so adjusted are held in place by spikes at H—E, and form a support for the joint, K, of the railroad rail. The spikes 70 are not shown, being the ordinary spikes of railroad use, but they fasten the shoes or bars to the ties and at the same time to the railroad rails where the device interlaces and interlocks with the bolt-heads and the nuts 75 preventing their turning out of place. The extension, M, of the outer base or shoe, G, passes beyond it for a secure adjustment of the base or shoe by the spikes which are driven in the notches at E—E. 80

I am aware that devices have been made for the locking of the nuts used in fastening fish bars to railroad rails. My invention, however, is not only an improvement upon these nut-locks as such, but from its form 85 and nature is a complete joint supporter at the same time.

What I claim and desire to secure by Letters Patent of the United States is:—

1. In a nut-holder and joint-supporter, 90 the combination of two metal bars or shoes, an inner and an outer, one of which is provided with a notched edge adapted to fit under and on two sides of the nuts of the bolts used for fastening railroad rails, each provided with an angular prolongation so as to permit it to pass over the lower edge of the railroad rail and under its entire width at each joint.

2. In a nut-holder and joint-supporter, a 100 device of the character described, comprising two metal bars or shoes, each having a notched

edge adapted to fit under and on two sides of the nuts used for fastening railroad rails, an angular prolongation on each bar passing over the edges of the railroad rails at its joint and across its entire width on the under side, with notches in the lower part of each bar adapted to receive fastening spikes.

In testimony whereof I have signed my name to this specification in the presence of two subscribing witnesses.

GEORGE W. HENRY, Sr.
